UNITED STATES PATENT OFFICE.

LAWRENCE H. MORSE, OF CLEVELAND, OHIO, ASSIGNOR TO THE AMERICAN MULTIGRAPH COMPANY, OF CLEVELAND, OHIO, A CORPORATION OF OHIO.

PRINTING-FORM HOLDER.

Application filed July 6, 1926. Serial No. 120,619.

This invention relates to printing devices. An object is to provide a flexible printing form which will be cheap to manufacture and which will securely retain printing slugs and hold them in proper position for printing. A further object is to provide a printing slug retaining device, employing parallel rails, which may be quickly mounted on and removed from a printing bed without disturbing the type. The specific object is to provide a simple and convenient printing form for use on a multigraph or other machine of that character.

In the multigraph, for example, the drum which supports the printing slugs has been provided with T headed rails rigidly secured to the drum at their bases. To so secure the rails, various methods have been followed, the best perhaps being to form the drum from reasonably soft metal, machine grooves therein parallel to the axis of the drum, mount the rails in the grooves, and then rivet the metal, between the grooves, down tightly against the base flanges of such rails. Obviously however when this is done, the rails must be left permanently on the drum. Further, metal which will readily rivet over is comparatively expensive, and the grooves must be carefully machined, so that each adjacent pair of rails will be practically the same distance apart in order that uniform slugs may be used.

By my invention I am enabled to use simply a cylindrical drum having a smooth outer surface, thereby saving considerable machining cost, and the drum may be of any metal, having sufficient strength, for example cast iron. Also, I have overcome certain objections to having the rails a permanent part of the drum. Further advantages and features are hereinafter more fully explained. The essential characteristics will be summarized in the claims.

In carrying out my invention I employ a sheet of suitable metal having upstruck lugs arranged in rows, certain of the lugs of each pair of adjacent rows extending toward each other to form in effect a shallow dove-tail groove. The rails are formed in the general shape of standard railroad rail, the flanges at the bottom being comparatively thin to fit the groove and the heads being so spaced that standard multigraph type slugs may have a reasonably close sliding fit therebetween.

In the drawings Fig. 1 is a transverse cross-section through a printing machine such as the multigraph, the paper feeding mechanism, the delivery mechanism, and other parts, being omitted; Fig. 2 is a fragmentary plan of one end of the printing device forming the subject of my invention; Fig. 3 is an enlarged fragmentary cross-section showing the sheet metal base and a number of rails retaining type slugs; Fig. 4 is a fragmentary perspective view showing the sheet metal base, the rails and a number of type slugs carried thereby; Fig. 5 is a perspective view of one of the rails; Fig. 6 is a perspective view of the slug retaining means such as shown in Fig. 4; Fig. 7 is a perspective view of the type slug.

Referring in detail to the drawings and indicating the various parts by suitable characters A represents the base and frame of a printing machine, B a printing drum carried thereby shown as comprising an arcuate carrying portion C and circular end members D. The drum may be carried by a shaft such as E extending therethrough and supported by the frame A. An impression roll is indicated at F.

In order that various printing forms made in accordance with my invention may be used interchangeably with the same printing machine without changing the drum, I may form the sheet metal base as indicated at 1, which may be wrapped around the arcuate portion C of the drum 3 and hooked, as at 3, over marginal ribs C' at one end, and similarly hooked over a rib G' of a pivoted plate G, shown as supported by the drum shaft. Means such as a series of set screws H, one being shown as bearing against the end of the portion C, may be used to tighten up the blanket and cause it to firmly embrace the peripheral surface of the drum. Inking means may comprise the ribbon J shown as fed from rolls R.

As shown most clearly in Fig. 4, the blanket has parallel corrugations 5, from the tops of which corrugations extend lips 6. As shown these lips are alternately placed along the corrugations, first on one side of a given corrugation and then on the other side. If desired these lips may be oppositely disposed or arranged in any manner, with or without the corrugations. For example, I may use any one of the constructions shown in the following patents: Clifton

Chisholm, No. 1,438,580; William Deming, No. 1,438,584; Burnie J. Craig, No. 1,438,582. The particular form herein shown is disclosed in the copending application of Justin 5 W. Macklin, Serial No. 76,298.

The T rails 10, which may be conveniently formed as shown in Fig. 5, each have a central web 11, T shaped heads 12 and base flanges 13, these flanges being comparatively 10 thin in order that they may be slid between the rows of lips 6 of adjacent corrugations without necessitating forming the lips at any considerable distance from the general outer 15 surface of the base plate. If desired the rails may be further secured by immersion of the blanket and the bases of the rails in a solder bath. The type, shown in Fig. 7, may be individual slugs 15, one for each letter as shown, or a longer slug containing several 20 letters if desired. The slugs 15 have head portions 16 and base portions 17 separated by grooves 18 substantially the width of the flanges which form the rail heads. As shown in Fig. 3, the bottom flanges of the slugs 25 may rest against the web portions of the rails to provide for alignment.

Any means may be used for holding the type slugs in place, such for example, as by 30 spring clips, one being shown at 20, Fig. 6 as having downwardly extending portions 21 with grooves 22 therein arranged to fit over the T heads of adjacent rails, the spring of the material forming such members 20, being sufficient to retain the member in 35 place once it is slipped between such adjacent rails.

It will be understood that the device may be used either on a drum or a flat type bed, since if the blanket were to lie flat, different 40 shaped rails might be provided to use the same slugs which are standard, or the arrangement could be reversed and the same rails used with thinner type. It will be also seen that, with the type removed, the blanket 45 may be laid flat for shipping and storing, since the rails will simply approach each other to allow such flattening.

From the above description it will be seen 50 that by reason of the reduced cost of material usable in the drum and of the fact that the drum does not have to be grooved as before to provide for mounting the rails, the expense involved is materially less, even with the cost of the blanket taken into account. Another advantage is that the 55 blanket can be easily removed for storing with the type in place, whereas by the former construction, in order to remove the type without disturbing the composition it was necessary to take off the entire drum. A 60 further advantage is that forms may be made up ahead of time; that is to say, while a given job is being printed, another composition may be made up on a different blanket 65 without involving material cost as compared

with having to provide several drums, and, in addition, having to tie up the machine while a drum is being replaced.

Having thus described my invention, I claim:

1. A printing device comprising in combination a plurality of T headed rails, type slugs adapted to be retained by the heads, a sheet metal base adapted to be wrapped around a printing drum to present said type 70 for printing, said sheet metal base being formed to retain the rails in position thereon.

2. A printing device comprising a blanket formed of sheet material having portions thereof severed and bent upwardly to form 80 lugs, said portions being arranged in rows, certain of the lugs extending in one direction and others extending in the opposite direction, and rails having grooves in their 85 opposite sides which rails are retained in place on the blanket parallel with each other and spaced apart by reason of said lugs engaging the base flanges of the rails beneath the grooves.

3. A printing device comprising a sheet 90 metal member having separated corrugations therein, lugs extending from the tops of said corrugations, each being severed along one edge and joined to the corrugations at the other, and type retaining rails 95 having flanged bases adapted to be slid under the said projections and to be retained against lateral movement with reference to the corrugations by the said corrugations.

4. A printing device comprising a sheet 100 metal member having upstanding parallel corrugations with lips projecting laterally in opposite directions from the tops of the corrugations, a plurality of rails grooved on the opposite sides to present overhanging 105 heads and projecting base flanges, said rails occupying the spaces between corrugations and held in place by lips engaging the base flanges, and type grooved on their opposite sides occupying the channels between the 110 rails, the heads of the rails occupying the grooves of the type.

5. A printing device comprising a sheet 115 metal member having lugs upstruck therefrom in rows, and type-slug retaining rails having flanged bases adapted to be held against said member by the lugs which overlap the base flanges, adjacent rails having space between them adapted to receive the feet of a row of grooved type.

6. A printing device comprising a sheet 120 metal member having rows of upstruck lugs, rails having grooves in their opposite sides and retained in place by the lugs, and type members extending between the rails and retained by means of projections on the type 125 members occupying said grooves.

In testimony whereof, I hereunto affix my signature.

LAWRENCE H. MORSE.
